US00D904024S

(12) **United States Design Patent** (10) Patent No.: **US D904,024 S**
(45) Date of Patent: ** Dec. 8, 2020

(54) **CASE**

(71) Applicant: **Apple Inc.**, Cupertino, CA (US)

(72) Inventors: **Vijay Karthik Koneru**, Los Angeles, CA (US); **Christopher Wiita**, West Hollywood, CA (US); **Duy P. Le**, Los Angeles, CA (US); **Guillaume Raoult**, San Francisco, CA (US); **Elvin Chu**, San Francisco, CA (US); **Martin Gschwandtl**, San Francisco, CA (US); **Christopher Kuh**, San Francisco, CA (US); **Robert Brunner**, Glen Ellen, CA (US)

(73) Assignee: **Apple Inc.**, Cupertino, CA (US)

(**) Term: **15 Years**

(21) Appl. No.: **29/722,473**

(22) Filed: **Jan. 30, 2020**

Related U.S. Application Data

(63) Continuation of application No. 29/690,695, filed on May 9, 2019, which is a continuation of application No. 29/685,004, filed on Mar. 25, 2019.

(51) **LOC (12) Cl.** **03-01**

(52) **U.S. Cl.** **D3/294**
USPC **D3/294**

(57)

CLAIM

The ornamental design for a case, as shown and described.

DESCRIPTION

FIG. 1 is a top front perspective view of a case showing the claimed design;

FIG. 2 is a bottom rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the figures show portions of the case that form no part of the claimed design.

1 Claim, 8 Drawing Sheets
